UNITED STATES PATENT OFFICE.

ERNEST KRAUSE, OF EL PASO, TEXAS.

THRESHOLD.

1,178,859.

Specification of Letters Patent. Patented Apr. 11, 1916.

Application filed September 4, 1915. Serial No. 49,073.

To all whom it may concern:

Be it known that I, ERNEST KRAUSE, a citizen of the United States, residing at El Paso, in the county of El Paso and State of Texas, have invented certain new and useful Improvements in Thresholds; and I do hereby declare the following to be a full, clear, and exact description of the invention, such as will enable others skilled in the art to 10 which it appertains to make and use the same.

My present invention relates to improvements in thresholds, and is especially intended to provide a resilient threshold which 15 will be adjustable to insure a tight joint with the bottom of the door, and will prevent the entrance of dust, wind, rain or snow.

The invention is also especially intended 20 to provide a threshold which will be cheap and simple in construction and may be readily adjusted to any particular door.

With these and other objects in view the invention consists in the novel details of 25 construction and in the combination and arrangement of parts which will be herein-after described and claimed.

Reference is had to the accompanying 30 drawings, in which similar parts are indicated by similar reference symbols throughout the several views, and in which:—

Figure 1 is a perspective view of the threshold, the door being indicated in dotted lines; Fig. 2 is a plan view of the device 35 shown in Fig. 1, parts being broken away; and Fig. 3 shows a section along the line 3—3 of Fig. 2 and looking in the direction of the arrows, the parts being on a larger scale than in the other figures.

40 A represents the bottom of the door, B the flooring and C the threshold which consists primarily of a plate of resilient metal, such as steel, brass, or the like, arched as at 1, and having laterally-projecting flanges 2 and 3, each flange being provided with a slot 4, and each slot having a series of indentations 5 adapted to engage the clamp screws 6 and 6^a. The flange 3 is bent under, as shown at 7 in Fig. 3, and terminates in a 45 vertical rib 8, through which pass the screw bolts 9 engaging the nuts 10. The heads 11 of these screw bolts are shouldered, and engage the shoulders 12 formed in the body of the plate 1, as shown most clearly in Fig. 3.

50 In order to mount the threshold, it is placed in the doorway in substantially the

position shown in Fig. 3, and the clamp screws 6 are secured in place, then the screw bolts 9 are turned until the arch 1 of the threshold plate fits snugly against the bottom of the door, and then the screws 6^a are screwed home, and the device is ready for use. 60

The resiliency of the threshold plate will enable the central portion 1 to be arched 65 more or less by simply turning up or easing down the screw bolts 9, causing the arched portion 1 to be raised or lowered as the case may be.

By having the slots 4 provided with a 70 series of notches 5, as shown, the clamp screws 6 and 6^a may be readily inserted so as to avoid seams or knots in the flooring or the like. Thus it will be seen that I provide an adjustable threshold made of substantially a single resilient plate of metal, which may be readily placed in position and readily adjusted to fit the bottom of the door, and the resiliency of the metal will always 75 form a tight joint while the door is closed. 80

While the device is especially applicable for use as a threshold with doors, it will be obvious that it may also be used in place of a weather strip for windows, gates, or the like. 85

It is obvious that those skilled in the art may vary the construction and arrangement of parts without departing from the spirit of my invention, and therefore I do not wish to be limited to such features except as 90 set out in the claims.

Having thus described my invention what I claim and desire to secure by Letters Patent of the United States is:—

1. A threshold comprising a single plate 95 of resilient metal having an arched central portion and laterally-projecting flanges, said flanges being provided with elongated slots with lateral notches in said slots, and one of said flanges being bent inward and terminating in an upwardly-projecting rib with screw bolts projecting from the opposite side of the arch, and passing through said upwardly-projecting rib, and nuts bearing against said rib and engaging said screw 100 bolts, substantially as described. 105

2. A threshold comprising a single plate of resilient metal having an arched central portion and laterally-projecting flanges, said flanges being provided with elongated slots 110 with lateral notches in said slots, and one of said flanges being bent inward and termi-

nating in an upwardly-projecting rib with screw bolts projecting from the opposite side of the arch, and passing through said upwardly-projecting rib, and nuts bearing against said rib and engaging said screw bolts, the arched portion of said plate being provided with shoulders to engage the heads of said screw bolts, substantially as described.

10 3. A threshold comprising a single plate of resilient metal having an arched central portion and laterally-projecting flanges, said flanges being provided with elongated slots, with screws engaging in said slots, and one of said flanges being bent inward and terminating in an upwardly-projecting rib with screw bolts projecting from the opposite side of the arch, and passing through said upwardly-projecting rib, and nuts bearing against said rib and engaging said screw bolts, substantially as described.

15 4. A threshold comprising a single plate of resilient metal having an arched central portion and laterally-projecting flanges, said flanges being provided with elongated slots, with screws engaging in said slots, and one of said flanges being bent inward and terminating in an upwardly-projecting rib with

screw bolts projecting from the opposite side of the arch, and passing through said upwardly-projecting rib, and nuts bearing against said rib and engaging said screw bolts, the arched portion of said plate being provided with shoulders to engage the heads of said screw bolts, substantially as described.

20 5. A threshold comprising a single plate of resilient metal having an arched central portion and laterally-projecting flanges, said flanges being provided with elongated slots, with screws engaging in said slots, and one of said flanges being bent inward and terminating in an upwardly-projecting rib with screw bolts projecting from the opposite side of the arch, and passing through said upwardly-projecting rib, and nuts bearing against said rib and engaging said screw bolts, the arched portion of said plate being provided with recessed portions having substantially vertical shoulders to engage the heads of said screw bolts, substantially as described.

25 In testimony whereof, I affix my signature.

ERNEST KRAUSE.
